UNITED STATES PATENT OFFICE.

JAMES OSA HAYES, OF WILLIS, OKLAHOMA.

DESIGN FOR A SAFETY MATCH-BOX.

49,118.

Specification for Design.

Patented May 30, 1916.

Application filed February 7, 1916. Serial No. 76,874. Term of patent 7 years.

To all whom it may concern:

Be it known that I, JAMES OSA HAYES, a citizen of the United States, residing at Willis, in the county of Marshall and State of Oklahoma, have invented a new, original, and ornamental Design for Safety Match-Boxes, of which the following is a specification, reference being had to the accompanying drawing, forming a part thereof.

Figure 1 is a perspective view; and Fig. 2

is a bottom plan view of a safety match box, showing my new design.

I claim:

The ornamental design for a safety match box, as shown.

JAMES OSA HAYES.

Witnesses:

O. H. DILLORD,

J. N. BATES.
